COMBINED WATER STRAINER AND SEA VALVE

Angus R. Gross, Jr., 1530 Russell St., Baltimore, Md.

Filed May 31, 1961, Ser. No. 65,403

Term of patent 14 years

(Cl. D91—1)

FIG. 1 is a front elevational view of a combined water strainer and sea valve showing my new design.

FIG. 2 is a side elevational view thereof.

FIG. 3 is a top plan view thereof.

FIG. 4 is a reduced fragmentary side elevational view thereof.

I claim:

The ornamental design for a combined water strainer and sea valve, substantially as shown.
